HYDRAULIC RETRACTOR CONTROL

Walter M. Pohl, New Haven, Conn., assignor to
Vickers, Incorporated, Detroit, Mich., a corpora-
tion of Michigan

Application October 1, 1941, Serial No. 413,126

8 Claims. (Cl. 60—52)

This invention relates to a hydraulic retractor control and has particularly to do with an improved control system for a hydraulic motor.

This application is a continuation in part of my copending application Serial No. 318,255, filed February 10, 1940.

An object of the present invention is to provide a hydraulic control system in which a novel arrangement of valves permits the continued movement of a motor to be effected by slight movement of the motor by an external force in the particular direction concerned.

A further object of the invention is the provision of a system which may operate automatically but may be fully controlled by manual operation. The hydraulic control system concerned herewith is especially adapted to the rammer mechanism of large guns in which it is desirable to have the retraction movement initiated by gun recoil. It is also adapted to a wide variety of commercial apparatus such as conveying machinery and the closing and opening of doors on industrial furnaces and machines where motion is continued after force impulse and further where motion interference by positive means unloads or relieves the circuit.

Other objects and features of the invention relating to the details of the hydraulic circuit and the operation thereof will be brought out in the following description and claims.

In the drawings:

Fig. 1 is a circuit diagram illustrating the invention.

Figs. 2 and 3 show modifications of a valve of Fig. 1 circuit.

An illustration of the principles of the invention will now be described in connection with the drawings.

Referring to Fig. 1 a piston 80 having a piston rod 81 is located in a cylinder 82. A main pressure source 14 and a pilot pressure source 15 are provided, as are also a relief valve 60 and the pilot pressure accumulator 61. A valve control housing is indicated generally at 83. In this valve control housing are formed valve bores 84, 85 and 86 and in an adjacent housing 87 is formed a valve bore 88.

The right end of cylinder 82, as viewed in the drawings, is connected to the valve block 83 by a conduit 89 which leads to valve bore 84. The left end of cylinder 82 is connected to the housing 83 by a conduit 90 which passes through the housing to connect to each of the valve bores 84, 85 and 86. A tank connection 91 connects to the valve bore 86 and a conduit 92 leading from

pump 14 is connected to each of the valve bores 86, 85 and 84 consecutively. Valve bores 84 and 85 are each provided respectively with annular recesses 93 and 94 connected by a passage 95. The conduit 92 terminates in an annular port 96 surrounding the bore 84. Slidable within the bore 84 is a plunger valve 98 urged downwardly by a spring 99 which is received in an axial recess at the top of the plunger. The lower end of the plunger is tapered at 100 and provided with an axial recess 101 opening to the lower end of the valve and also to a transverse passage 102 which opens into the port 96. An annular restriction 103 is provided in the plunger 98 for purposes which will be described. In the lower portion of the bore 84 is a piston 105 which has a tapered end 106 upon which rests the tapered end 100 of plunger 98. In the top portion of the bore 85 is a slideable plunger valve 108 urged downwardly by a spring 109 received in an axial recess in the plunger. The lower end of the plunger 108 is tapered as shown at 110 and rests upon a tapered upper end 111 of a plunger 112 located in the lower portion of the bore 85. The tapered end 110 is provided with a restricted axial bore 113 and cross bore 114 connected to the hollow center, the purpose of which will be explained below.

Slidably positioned in valve bore 86 is a valve spool 115 which is provided with enlarged heads 116, 117 and 118. A spring 119 acting on suitable washers serves to urge the valve 115 to the neutral position shown in the drawings. Directly below the valve 115 is mounted a piston 121 shiftable in housing 87.

Taking up now the pilot circuit, within the bore 88 in housing 87 is a pilot valve 123 centered by a spring 124 and provided with heads 125 and 126. Valve 123 receives pilot pressure from a conduit 127 and when in the position shown, it passes this pressure to a conduit 128 leading up in the housing 83 between valve bores 84 and 85. Valve bores 84 and 85 are each provided with annular ports 129 and 130, respectively, which are connected to passage 128. Valve 123 is adapted to be shifted to direct pilot pressure either to the lower end of piston 105 or the lower end of piston 112 through conduits 131 and 132 leading to bores 84 and 85 respectively. Valve 123 is provided with an axial recess 133 which is open to the left end of the valve through a port 134 and which opens at the right end of the valve to a tank chamber 135. Conduit 135a connects chamber 135 to the tank. Spaced from ports 129 and 130 surrounding bores 84 and 85 are similar

ports 136 and 137. The valve plunger 98 is provided with an annular restriction 138 which is adapted to connect the port 129 with the port 136 when the valve is shifted upwardly and which connects the port 136 with a tank port 139 when the valve plunger is in the position shown. Valve plunger 108 is provided with an annular restriction 140 which is adapted to connect the port 130 with the port 137 when valve plunger 108 is shifted upwardly and which connects port 137 with a tank port 141 when the valve plunger 108 is in the position shown. Port 136 is connected by a conduit 143 to the top end of valve bore 86 and port 137 is connected to the lower end of piston 121 by a conduit 144. The chamber directly above the piston 121 is a tank chamber connected also to the chamber 135 at the right end of valve 123. The chamber behind valve 108 is connected through passage 108a and check valve 108b to conduit 90.

Fig. 1 shows the control system in neutral position with the pumps not running. When the pumps 14 and 15 are started, fluid from pump 14 will pass from conduit 92 up through the bore 86 around valve head 117 to the tank conduit 91. Also the pilot pump 15 will deliver pressure to the accumulator piston 62 to lift the same and cause a spilling of pressure through the tank opening 63. In this manner a reserve supply of fluid is stored in the accumulator. A ramming stroke is initiated by manually shifting pilot valve 123 to the left by means of a hand lever 150. Shifting of this valve 123 will admit pilot pressure from the conduit 127 to conduit 131 and the lower working area of piston 105 to cause shifting of piston 105 and plunger valve 98 upward. In this position pilot pressure from conduit 128 may pass from port 129 to port 136 and then to the top of bore 86 to shift valve 115 down.

This shifting of valve 115 down will make a free connection between conduit 90 of cylinder 82 and tank conduit 91 and will also cause pressure from conduit 92 to pass the tapered ends 106 and 100 of piston 105 and valve plunger 98 to the conduit 89 and piston 80. As the piston 80 stands in the drawings, it has just completed a ramming stroke. During this advance stroke, valve plunger 98 was shifted to its upper position by piston 105. This initiated the stroke of piston 80 and during the stroke of piston 80 the valve plunger 98 was gradually returning to its static position (as shown in Fig. 1) by reason of the fact that the spring 99 was urging the piston down and liquid was passing gradually from chamber 96 through restricted passages 102 and 101 to the chamber 84 behind the valve. The hand lever 150 may be released without affecting the motion of the motor. In the upper position of valve 98, the conduit 89 is cut off from the port 93. At the completion of the ramming stroke the piston 80 will be stopped by contact with the cylinder 82 and by this time the valve 98 will probably have reached its position shown in Fig. 1. When valve 98 is fully restored to its lower position, the chamber at the upper part of the bore 86 will be vented thus allowing spring 119 to return valve 115 to its neutral position as shown. The flow from the operating pump 14 will then be diverted to the tank.

It is desirable that valve 98 move to its upper or operative position quickly and move down to its static position slowly for which reason a check valve 98a to the left of valve 98 and restricted orifice 101 are incorporated in the design. As valve 98 moves up, fluid from area 84 above the

valve is freely exhausted through the check valve 98a, port 86, line 92, past valve 115 to tank line 90-91. As the valve 98 moves down, the incoming fluid is metered slowly through the restricted orifice 101, thus retarding the downward motion of the valve. The size of restriction 101 is important in that valve 98 must not reach a position closing 96 from 89 until the completion of the stroke of 80. If, however, an obstruction blocks the movement of the piston 80, valve 98 will continue to move to its down position to relieve pressure. The rammer is especially useful for a short fast stroke and it is desirable that valve 98 reach a position closing 96 from 89 substantially at the end of the stroke of 80.

The retraction stroke may be initiated either by the manipulation of the control lever 150 or by a slight movement of the piston 80 by the application of an extraneous force such as a gun recoil. When the hand lever 150 is used, the valve 123 will be shifted to the right and pilot pressure from conduit 127 will be admitted to conduit 132 and the lower end of bore 85. This will lift piston 112 and the plunger valve 108 so that pilot pressure from conduit 128 may pass through port 130 to port 137 and conduit 144 to the lower end of piston 121. This will shift valve 115 upwardly thereby blocking the tank conduit 91 and opening the conduit 90 to the pressure conduit 92. Pressure will then be directed to both ends of piston 80 since one end is in direct connection with conduit 90 and the right end will be connected to conduit 90 through valve bore 85, port 94, passage 95, port 93, valve bore 84, and conduit 89. As the effective area at the left end of the piston 80 is greater than the right end, the piston will advance to the right by the differential between the two hydraulic forces. Once the piston motion is started, valve 108 will be maintained in open condition by virtue of the fact that flow from the lower end to the upper end of the valve 108 is through restricted orifices 113 and 114; the hand lever may be released without affecting the operating phase. This movement will continue until the piston is brought to rest by positive contact with the end of the cylinder at which time valve plunger 108 will be fully returned to its normal position by spring force, the lever 150 having been previously released. In this slow return movement valve 108 operates in the same manner as described in connection with valve 98.

The retraction motion may also be initiated by the extraneous force on the piston and the immediate effect of this force will be pressure on the lower end of plunger 108 through conduit 89, valve bore 84, port 93, passage 95 and port 94. This pressure will shift valve 108 upwardly and connect conduit 128 and port 130 with port 137 and conduit 144. The result will be a shifting upwardly of the valve 115 as previously described in connection with the manual operation and the remainder of the action is the same.

The arrangement shown in Fig. 1 is designed to insure completion of the ramming stroke irrespective of the shifting of the control lever after the stroke has started; i. e., after a ramming stroke has been initiated it will continue until completed, even though the control lever is shifted to the neutral or retract position. During the retraction stroke, however, the operator may take charge at any time and reverse the motion by shifting the control lever to "Ram."

The operating principles which make this possible will be clearly understood. During a ram-

ming stroke valve 115 is held in the ram position by pilot pressure applied to the large area 116. Shifting the control lever to retract admits the same pressure to the under side of small piston 121, which tends to force it upward but is prevented from doing so because of the greater force acting on valve 115 to hold it down. During a retraction stroke, however, valve 115 is held in the "Retract" position by pilot pressure applied to the small piston 121, but at any time during the retraction stroke the motion may be reversed by shifting the control lever to "Ram," thereby admitting pilot pressure to the larger area 116, at which time valve 115 will be shifted to the ram position.

Some applications require that the retraction stroke be completed irrespective of the shifting of the control lever but that it be possible for the operator to take charge and reverse the motion at any time during the ramming stroke. This may be accomplished by modifying the design in accordance with Fig. 2, in which piston 121a is made with a greater area than that of 116.

Fig. 3 shows a further modification in which it is possible for the operator to take charge and reverse the motion at any time during either the ramming or retraction stroke. In this design areas 121b and 116 are equal and if pilot pressure is applied to both at the same time the hydraulic forces acting on valve 115 will be balanced and it will be returned to neutral by the centering spring, thus diverting flow from pump 14 to tank. The immediate effect of this will be a momentary stopping of piston 80 while valve 98 or 108 (as the case may be) recovers its normal spring impelled position, after which motion of the piston will take place in the direction required by the position of the control lever.

A check valve 155 in conduit 91 connects the tank with valve recess 86. This check valve functions only during the period that piston 80 is being moved in the retract direction by an extraneous force. Its purpose is to permit oil to be drawn into the cylinder directly from the tank, thus assuring an ample supply of oil to replace the vacuum which would otherwise be created by the retreating piston. At such times, if the piston velocity is quite high, the pump would not have sufficient capacity to supply the necessary fluid.

What I claim is:

1. In a hydraulic system, a main pressure source, a reversible motor means to be actuated by pressure from said source, said motor having a limited movement in each direction and a control system in a hydraulic circuit between said pressure source and said motor comprising a source of pilot pressure, a main valve for controlling the direction of movement of said motor by controlling the output of said main pressure source, a pilot pressure chamber at each end of said valve to permit the same to be pilot operated, a manually operable pilot control valve for directing pressure from said pilot source, a first auxiliary valve shiftable from a static position in response to pilot pressure from said manually operated pilot valve to an operating position for directing pilot pressure to one end of said main valve, and a second auxiliary control valve shiftable from a static position in response to pilot pressure from said manually operated control valve to an operating position adapted to direct pilot pressure to the other of said main valve pilot chambers, means tending to move each of said auxiliary valves to static position, each of

said valves being retarded in movement from an operative position to a static position after initial shifting to operative position by reason of a restricted passage connecting a closed chamber at one end of the valve to operating pressure at the other end of the valve.

2. In a hydraulic system, a main pressure source, a reversible motor means to be actuated by pressure from said source, said motor having a limited movement in each direction and a control system in a hydraulic circuit between said pressure source and said motor comprising a source of pilot pressure, a main valve for controlling the direction of movement of said motor by controlling the output of said main pressure source, a pilot pressure chamber at each end of said valve to permit the same to be pilot operated, a manually operable pilot control valve for directing pressure from said pilot source, a first auxiliary valve shiftable from a static position in response to pilot pressure from said manually operated pilot valve to an operating position for directing pilot pressure to one end of said main valve, and a second auxiliary control valve shiftable from a static position in response to pilot pressure from said manually operated control valve to an operating position adapted to direct pilot pressure to the other of said main valve pilot chambers, means tending to move each of said auxiliary valves to static position, each of said valves being retarded in movement from an operative position to a static position after initial shifting to operative position by reason of a restricted passage connecting a closed chamber at one end of the valve to operating pressure at the other end of the valve, one of said auxiliary valves being responsive to movement of said motor by an external force in a direction opposite to that instituted by the other auxiliary valve to effect continued operation of said motor in the direction instituted by the external force.

3. In a hydraulic system, a pressure source, a motor means to be actuated by pressure from said source, control valve means for directing liquid under pressure from said source to said motor to control the starting, stopping and direction thereof, pilot chambers at each end of said control valve to effect shifting thereof, and pilot valve means for directing pressure to said chambers selectively and simultaneously to control the position of said control valve, the effective pressure areas in said pilot chambers being related to effect predetermined shifting and consequent change in the position and function of said control valve during periods when pressure is directed simultaneously to said pilot chambers by said pilot valve means.

4. In a power transmission system, a hydraulic motor, a source of pressure for driving said motor, a main pilot valve means for controlling the flow of pressure liquid to and from said motor, a source of pilot pressure, a series of three valves connected to control said pilot pressure, two of said three valves being arranged to control, alternately, shifting of said main pilot valve means, and one of said three valves being arranged to control shifting of said other two valves.

5. In a power transmission system, a hydraulic motor, a source of pressure for driving said motor, a main pilot valve means for controlling the flow of pressure liquid to and from said motor, a source of pilot pressure, a series of three valves connected to control said pilot pressure, two of said three valves being shiftable from neutral to operative positions to control, alternately, shifting

of said main pilot valve means, and the third of said three valves being arranged to control shifting of said first two valves, said first two valves each comprising a valve member slidible in a bore and provided with restricted passages between the ends thereof arranged to be subject to motor operating pressure when either of the first two valves is actuated from neutral, means biasing each of said valves toward a neutral position, closed chambers behind said first two valves whereby pressure passes through said passages to said chamber subsequent to actuation of one of said first two valves to effect delayed restoration of the shifted valve to neutral.

6. In a power transmission system, a hydraulic motor, a source of pressure for driving said motor, a main pilot valve means for controlling the flow of pressure liquid to and from said motor, a source of pilot pressure, a series of three valves connected to control said pilot pressure, two of said three valves being shiftable from neutral to operative positions to control, alternately, shifting of said main pilot valve means, and the third of said three valves being arranged to control shifting of said other first two valves, said first two valves each comprising a valve member slidible in a bore and provided with restricted passages between the ends thereof arranged to be subject to motor operating pressure when a valve is actuated from neutral, closed chambers behind said valves, whereby pressure passes through said passages to said chamber subsequent to actuation of either of said first two valves to effect delayed restoration of the shifted valve to neutral, and means connecting each of said chambers to a motor operating pressure line arranged to permit exhaust of said chamber during movement of its respective valve and to prevent exhaust during operation of said motor.

7. In a power transmission system, a hydraulic

motor, a source of pressure for driving said motor, a main pilot valve means for controlling the flow of pressure liquid to and from said motor, a source of pilot pressure, and two valves connected to control said pilot pressure and arranged to control alternately, shifting of said main pilot valve means, said two valves each comprising a valve member slidible in a bore from a neutral to operative position and provided with restricted passages between the ends thereof arranged to be subject to motor operating pressure when either of said two valves is actuated from neutral, closed chambers behind said two valves whereby pressure passes through said passages to said chambers subsequent to actuation of one of said two valves to effect delayed restoration of the shifted valve to neutral.

8. In a power transmission system, a hydraulic motor, a source of pressure for driving said motor, a main pilot valve means for controlling the flow of pressure liquid to and from said motor, a source of pilot pressure, and two valves connected to control said pilot pressure and arranged to control, alternately, shifting of said pilot means, said two valves each comprising a valve member slidible in a bore from a neutral to operative position and provided with restricted passages between the ends thereof arranged to be subject to motor operating pressure when either of the two valves is actuated from neutral, closed chambers behind said valves whereby pressure passes through said passages to said chambers subsequent to actuation of one of said valves to effect delayed restoration of the shifted valve to neutral, and means connecting each of said chambers to a motor operating pressure line arranged to permit exhaust of said chamber during movement of its respective valve and to prevent exhaust during operation of said motor.

WALTER M. POHL.
